E. MORRISON,
FASTENER FOR FRUIT CASES,
APPLICATION FILED DEC. 16, 1918.

1,359,823.

Patented Nov. 23, 1920.

FIG. 1.

FIG. 2.

FIG. 3.

Inventor:
Edward Morrison
per H. W. Blucker
Attorney.

UNITED STATES PATENT OFFICE.

EDWARD MORRISON, OF WARKWORTH, AUCKLAND, NEW ZEALAND.

FASTENER FOR FRUIT-CASES.

1,359,823.

Specification of Letters Patent. Patented Nov. 23, 1920.

Application filed December 16, 1918. Serial No. 266,987.

To all whom it may concern:

Be it known that I, EDWARD MORRISON, a citizen of the Dominion of New Zealand, and residing at Hepburns Creek Road, Warkworth, Auckland, in the Provincial District of Auckland, in the Dominion of New Zealand, have invented certain new and useful Improvements in Fasteners for Fruit-Cases, of which the following is a specification.

10 This invention provides a fastener for cases and is more particularly applicable to cases used repeatedly for the transport of fruit, produce and the like.

15 The fastener is applied to a hinged lid and is made of flat steel secured to the lid, and passes through a recess in a batten fixed to the case. A hole in the fastener is adapted to engage a stud projecting from the case, and the batten prevents the fastener from being 20 inadvertently released.

An adhesive label is affixed over the end 25 of the fastener, so that the case cannot be opened by an unauthorized person without detection. The label is preferably printed with the device of a trade mark.

The drawing herewith illustrates the invention:—

Figure 1, is a perspective view of a case embodying the invention,
30 Fig. 2, is a part longitudinal sectional elevation of the case embodying the invention, and

Fig. 3, is a part front elevation of a case embodying the invention.

35 The fastener 1 is made of band steel and affixed to the lid 2 of a case 3 and is secured by screws or nails 4 and a batten 5 fixed to the lid and passing over the fastener.

The fastener extends down the end 6 or 40 side of the case, and between a batten 7 and the case, the said batten being fixed to the case and having a recess 8 to allow the fastener to pass.

A hole 9 in the fastener is adapted to engage a stud 10 projecting from the case below 45 the batten 7, and the end 11 of the fastener is bent slightly to afford a grip for releasing the fastener from the stud.

By passing the fastener through the recess 8 the certainty of the fastener being engaged 50 by the stud 10 is assured, and the straining or deforming of the fastener is also prevented thereby.

The adhesive label 12 is affixed to the end 6 and lid 2 and covers the extension of the 55 fastener.

What I claim and desire to secure by Letters Patent of the United States is:—

1. The combination, with a case and a lid for said case, of an L-shaped fastener having 60 a shank secured to said lid and the other shank adapted to lie against a wall of said case, the latter shank being provided with a hole, a batten secured to said wall, said batten having a recess allowing the latter shank 65 to pass therethrough, and a stud on said wall for engaging said hole.

2. The combination, with a case and a lid for said case, of battens secured to said lid and to a wall of said case respectively, an 70 L-shaped metal piece having a shank extending between the lid and the adjacent batten and secured to said lid, and a shank adapted to lie against said wall and pass through a recess in the batten secured to said wall, the 75 latter shank being bent at its outer end and provided with a hole near said outer end, and a stud on said wall below the last mentioned batten for engaging the said hole.

In testimony whereof I have signed my 80 name to this specification in the presence of two witnesses.

EDWARD MORRISON.

Witnesses:

W. S. McCONNELL,
K. WALLACE.
